FLOW DEVICE

Jon R. Long, Fort Worth, Tex.

Application April 19, 1935, Serial No. 17,215

7 Claims. (Cl. 103—232)

This invention relates to new and useful improvements in flow devices.

One object of the invention is to provide an improved flow device including a valve of the 5 stage lift type, a plurality of which are mounted at different elevations in the tubing of a well for admitting gas, or other fluid pressure into the tubing, whereby the well fluid within said tubing at each valve is elevated by the pressure introduced at that particular valve.

An important object of the invention is to provide an improved stage valve which is operated by the velocity of the well fluid passing upwardly in the tubing, whereby a minimum of gas or air 15 pressure is necessary to flow any type of well.

Another object of the invention is to provide an improved stage lift valve which positively prevents downward flow of the well fluid through the tubing as soon as said fluid stops upward flow 20 therethrough, and means for introducing gas or air pressure above the cut-off means whereby the well fluid thereabove is elevated, the positive cut-off reducing slippage, thereby providing for more efficient flowing of the well.

Another object of the invention is to provide 25 improved means for flowing wells including a plurality of stage valves mounted at different elevations in the tubing, said valves being so arranged that they may be spaced irrespective of 30 the fluid level in the well, each valve having means for positively cutting off downward flow of the well fluid therethrough, whereby the fluid is positively lifted in stages, the tubing remaining full of fluid at all times, which permits 35 flow to start immediately upon the release of gas or air pressure into the tubing through the valves.

A further object of the invention is to provide 40 an improved stage valve for controlling the flow of well fluid through the well tubing and also for controlling the introduction of air or gas pressure, for flowing the well, into the tubing, said flow control and pressure control co-acting with each other according to the velocity of the well 45 fluid flowing through the valve.

A still further object of the invention is to provide a stage valve which is so arranged that sand, or other abrasive material present in the well will not accumulate in the working parts 50 thereof to interfere with the operation thereof, whereby the efficiency of said valve is increased and the life thereof prolonged.

A construction designed to carry out the 55 invention will be hereinafter described, together with other features of the invention.

The invention will be more readily understood from a reading of the following specification and by reference to the accompanying drawings in which an example of the invention is shown, and 60 wherein:

Figure 1 is a longitudinal sectional view of a well, showing stage valves constructed in accordance with the invention, connected in the tubing,

Figure 2 is a longitudinal sectional view of the stage valve, with the valve plunger in a lowered 5 position,

Figure 3 is a view, similar to Figure 2, showing the valve plunger in a raised position,

Figure 4 is a horizontal, cross-sectional view 10 taken on the line 4—4 of Figure 2,

Figure 5 is a horizontal, cross-sectional view, 15 taken on the line 5—5 of Figure 2,

Figure 6 is an enlarged vertical, sectional view of the upper end of the valve plunger, and

Figure 7 is a horizontal, cross-sectional view, 20 taken on the line 7—7 of Figure 3.

In the drawings the numeral 10 designates a cylindrical housing or casing, which is internally screw-threaded at its upper and lower ends, whereby it may readily be connected in the tubing A of a well. An elongated cylinder 11 is disposed axially within the housing at the mid-portion thereof and is supported by webs 12, which are preferably made integral with the housing. The webs and cylinder form a spider, which extends transversely within the housing, and it is pointed out that all sharp corners are eliminated in forming the web, whereby turbulence of the upwardly flowing fluid through the spider is reduced to a minimum.

A cylindrical plunger 13 is slidable vertically within the cylinder and has a snug sliding fit therein. The plunger is of a greater length than the cylinder, whereby its upper and lower ends extend beyond the ends of said cylinder. The upper end of the plunger is provided with a valve head 14, which is arranged to engage a valve seat 15 formed on the upper side of a ring 16 which is screwed into the housing above the spider, (Figure 2). The valve and seat are preferably ground so as to assure a positive seal. When the well is flowing upwardly through the tubing A, the pressure thereof beneath the valve head will raise said head and plunger to permit fluid to flow upwardly past the valve and seat. However, should the well fluid lose its velocity and begin to fall downwardly in the tubing, the valve would immediately close to positively prevent downward flow through the tubing.

It is pointed out that the valve head 14 and seat 15 are located at a distance above the spider. Therefore, any sand or sediment present in the fluid will not accumulate on the spider and in the cylinder between the walls thereof and the plunger. This sand and sediment will accumulate 55 on the valve head and seat and when the valve is again raised, as will be explained, the well fluid will carry the same upwardly therewith. Thus, these abrasive materials are prevented from seeping into the cylinder and interfering with the 60

operation of the plunger, thereby prolonging the life of the entire structure.

The lower end of the plunger 13 is threaded to receive a circular nut 18 which has a greater diameter than the plunger. A cotter key 19 extends diametrically through the screw-threaded portion of said plunger beneath the nut to prevent its unscrewing therefrom. The extreme lower end of the plunger is rounded and the sharp lower edge of the nut is also rounded, so as to reduce resistance to the upward flow of the well fluid through the housing 10. It is obvious that when the plunger is raised by the well fluid raising the valve head 14, the nut 18 will strike the lower end of the cylinder to limit the upward movement of the plunger.

For introducing gas or air pressure from the casing B of the well into the tubing to flow the well when the same cannot flow itself, the webs 20 12 of the spider are provided with radially extending ducts 20 (Figures 2 and 5). The ducts extend from the outer periphery of the housing 10 to the exterior of the cylinder 11, whereby air or gas pressure within the casing B of the well is introduced into the cylinder 11. The plunger 13 is formed with an annular peripheral groove 21, which is located so that when said plunger is in a lowered position and the valve head 14 seated, the groove registers with the ducts 20. Thus, it will be seen that with the plunger lowered, gas or air pressure from the casing B enters the annular groove 21 in the plunger.

From the groove this gas or air pressure passes through radial ports 22 in the plunger. These ports 22 have their inner ends connected with the lower end of an axial passage 23, which extends upwardly through the plunger into the valve head 14. The extreme upper end of the passage is enlarged at 24, whereby a shoulder 25 is formed. This shoulder is provided with an annular valve seat 26 which is arranged to be engaged by a ball 27, whereby the passage 23 is closed.

The enlarged portion 24 is internally screw-threaded to receive an annular nozzle 27' (Figure 45 6). The nozzle is provided with upwardly convergent ducts 28 which extend from the lower end of said nozzle and incline upwardly toward each other. The upper ends of the ducts communicate with an axial outlet 29 in the upper end of the nozzle. The lower ends of the ducts 28 are spaced so that when the ball 27 is raised by the gas or air pressure passing upwardly through the passage 23, said ball will not close the ducts but will engage the underside of the nozzle 55 at the central portion thereof. Thus it will be seen that when the plunger 13 is in a lowered position with the valve head 14 engaging the seat 15, the gas or air pressure from the casing B of the well will flow through the ducts 20, ports 22 and upwardly through the passage 23. This pressure will unseat the ball valve 27 and pass through the nozzle 27' into the tubing A above the valve head 14, which will elevate the well fluid which is trapped above the head 14.

In operation any desired number of the stage valves are connected in the tubing. The valves are spaced according to the amount of air or gas pressure in the casing A. Assuming that the well on which installation is made does not produce sufficient gas to flow the well, it is necessary to introduce auxiliary gas or air into the casing. As shown in Figure 1, the tubing A is packed off from the casing B at the lower end thereof by a packer C. The upper end of the casing is closed and a lead pipe 30, connected with a suit-

able source of air or gas supply is entered into the casing. It is obvious that as the pressure builds up in the casing, the air or gas pressure will enter the uppermost stage valve to elevate the well fluid thereabove. This starts the well flowing and as the valve head 14 unseats, the gas or air supply to this valve is cut off due to the plunger 13 moving upwardly within the cylinder, which movement causes the groove 21 to move out of registration with the radial ducts 20 in the web, thereby closing said ducts.

The gas or air pressure then enters the tubing at the stage valve next therebelow and sequentially at each lower stage. It is obvious that when flow starts, the well fluid is positively lifted in stages. That is, assuming the well fluid has sufficient pressure to unseat the valve head 14, then such fluid flows upwardly thereby. At this time the gas or air pressure is cut off, due to the upward movement of the plunger. When the velocity of the fluid has decreased and said fluid starts to fall back through the tubing, the valve head 14 immediately seats to trap the fluid thereabove. The seating of the valve head lowers the plunger 13 to permit gas or air pressure to enter the tubing. This pressure is sufficient to raise the column of well fluid above the valve head 14 to the next stage valve, which valve lifts it to the next above valve, and so on until the fluid is raised to the surface.

It is pointed out that the valve head 14 positively cuts off any downward flow of the well fluid through the tubing. The seating of this valve is accomplished by the weight of the well fluid thereabove, and this valve remains closed until the gas pressure ejecting from the nozzle has raised the fluid column which permits the well fluid to unseat said valve head and permit another column of fluid to flow thereby.

The action of the valves is entirely automatic, the gas or air pressure from the well casing B being admitted only when the flow through the tubing has stopped. The pressure is cut off immediately when flow through the stage valve again starts. This action reduces the gas or air necessary, to flow the well, to a minimum. The positive cut off of the downward flow makes the valve adaptable for use in all types of wells, regardless of the production. That is, it may be used on wells producing oil, wells producing oil and gas, wells producing oil and water, or wells where highly corrosive elements are encountered. The valves have been found particularly adaptable in flowing mud from the well, which is made possible because of the positive stage lift action.

In Figure 1, auxiliary air or gas pressure is introduced into the casing B through the inlet pipe 30. In some cases, the well produces sufficient gas to flow the well and in such event, the pipe 30 is eliminated, as is the packer. The top of the casing remains covered and gas rising in the casing B from the oil bearing sand is utilized to operate the stage valves. In still other cases, gas bearing strata may be present at a point above the bottom of the hole. If this occurs, the packer C remains in position as shown in Figure 1, but the pipe 30 is eliminated. The well casing B is perforated at the level of the gas bearing strata and the gas therefrom enters the casing and is utilized to elevate the fluid, being admitted through the stage valves.

The device has been found particularly adaptable to removing mud from a well. In using the same for this purpose, the drill stem (not shown) 75

is removed from the casing B. The latter is, of course, practically full of mud. The tubing A, having the valves 10 connected therein is then run into the casing as shown. The upper end 5 of the casing is closed as fluid pressure is entered into the casing. Due to the fact that the valves operate so as to positively cut off a downward flow through the tubing, it is obvious that the mud is lifted by stages from the well.

10 What I claim and desire to secure by Letters Patent is:

1. A flow device arranged to be connected in a well tubing within a well casing and including, a housing, a valve within the housing arranged to be reciprocated endwise by the well fluid within the tubing relative to a flow checking seat part 15 of the housing whereby to open to permit upward flow of fluid through the tubing and to close to prevent downward flow of liquid through and from the tubing and means co-acting with the valve comprising communicable passages in the valve and housing to admit fluid under pressure from the well casing constantly into the housing below the valve seat part and into the tubing 20 above said valve when the valve is closed, whereby the well fluid thereabove is elevated.

2. A flow device arranged to be connected in a well tubing including, a housing, a cylinder supported within the housing and communicating with the casing of the well, whereby pressure fluid from the casing is conducted to the cylinder, a valve above the cylinder actuated by the well fluid arranged to open to permit upward flow of the well fluid through the tubing and arranged to close to prevent downward flow of liquid through and from the tubing and a plunger having means for conducting pressure fluid therethrough and depending from the valve and slideable in the cylinder for controlling the admission of pressure fluid from the cylinder to the tubing above the valve, said pressure fluid conducting means being active only in the closed position of the valve.

3. A flow device arranged to be connected in a well tubing including, a housing, a cylinder supported within the housing and communicating with the casing of the well, whereby pressure fluid from the casing is conducted to the cylinder, a valve above the cylinder actuated by the well fluid arranged to open to permit upward flow of the well fluid through the tubing and arranged to close to prevent downward flow of liquid through and from the tubing, and a plunger having passages for conducting pressure fluid therethrough and being actuated by the valve and slideable in the cylinder for controlling the admission of pressure fluid from the cylinder to the tubing above the valve, said plunger being so arranged as to permit admission of pressure fluid to the tubing when the valve is closed and to cut off 55 said pressure fluid when the valve is open.

4. A flow device arranged to be connected in a well tubing including, a housing, a cylinder supported within the housing and communicating with the casing of the well, whereby pressure fluid from the casing is conducted to the cylinder, a valve seat located at a distance above the cylinder, a valve actuated by fluid adapted to engage the seat and arranged to unseat to permit upward flow of the well fluid through the tubing 60 and arranged to close to prevent downward flow of liquid through and from the tubing, and a plunger depending from and actuated by the valve and slideable in the cylinder for controlling

the admission of pressure fluid from the cylinder to the tubing above the valve, said plunger having communicable passages for conducting pressure fluid active only in the closed position of the valve.

5. A flow device arranged to be connected in a well tubing including, a housing, a cylinder of smaller diameter than the housing located axially therein, transverse webs for supporting said cylinder whereby well fluid within the tubing may flow by said cylinder, said webs having radial ports extending from the outer wall of the housing to the cylinder so that fluid under pressure within the well casing is conducted to the interior of the cylinder, a valve above the cylinder actuated by the well fluid and arranged to open to permit upward flow of the well fluid of liquid through and from the tubing and also to close to prevent downward flow therethrough, and a plunger depending from the valve and slideable in the cylinder for controlling the admission of pressure fluid from the cylinder to the tubing above the valve, said plunger having pressure fluid conducting passages communicable with said radial ports of the cylinder in the closed position only 25 of the valve.

6. A flow device arranged to be connected in a well tubing including, a housing, a cylinder of smaller diameter than the housing located axially therein, transverse webs for supporting said cylinder whereby well fluid within the tubing may flow by said cylinder, said webs having radial ports extending from the outer wall of the housing to the cylinder so that fluid under pressure within the well casing is conducted to the cylinder, a valve seat located at a distance above the cylinder, a valve actuated by fluid adapted to engage the seat and arranged to unseat to permit upward flow of the well fluid through the tubing and also to close to prevent downward flow of liquid through and from the tubing, and a plunger depending from and actuated by the valve and slideable in the cylinder for controlling the admission of fluid pressure from the cylinder to the tubing above the valve, said plunger having an axial pressure fluid passage extending with its upper end communicably to the top of the valve and its lower end being communicable with said radial ports of the cylinder in the closed position only of the valve.

7. A flow device arranged to be connected in a well tubing within a well casing and including, a housing, flow control means within the housing comprising a valve member arranged to be opened by the well fluid to permit upward flow of liquid through the tubing and arranged to be closed to prevent downward flow of liquid through and from the tubing, and means co-acting with said flow control valve member for admitting fluid under pressure from the well casing into the tubing when said flow control valve is closed, said means comprising a supporting portion within said housing provided with pressure fluid conducting means communicable with the well casing, and the valve member having a plunger extension operating in said support and provided with an axial passage having an upwardly opening check valve in its upper end portion and communicable at its lower end with the pressure fluid conducting means of said valve supporting portion of the housing.
